(57) CLAIM

We claim the ornamental design for a document validator, as shown.

DESCRIPTION

FIG. 1 is a front elevation view of the document validator according to our new design;

FIG. 2 is a rear elevation view thereof;

FIG. 3 is a right side elevation view thereof;

FIG. 4 is a left side elevation view thereof;

FIG. 5 is a plan view thereof;

FIG. 6 is a bottom view thereof;

FIG. 7 is a front perspective view thereof from right upper side; and,

FIG. 8 is a rear perspective view thereof from left upper side. The broken lines in FIG. 6 represent unclaimed subject matter.
